DESIGN FOR A TEXTILE FABRIC OR SIMILAR ARTICLE

Johnnye Lee Vorhauer, Chicago, Ill., assignor to Reliance Manufacturing Company, Chicago,
Ill., a corporation of Illinois, doing business as
The Sterling Company

Application January 18, 1937, Serial No. 67,116

Term of patent 3½ years

To all whom it may concern:

Be it known that I, Johnnye Lee Vorhauer, a citizen of the United States, residing at Chicago, in the county of Cook and State of Illinois, have invented a new, original, and ornamental Design for a Textile Fabric or Similar Article, of which the following is a specification, reference being had to the accompanying drawing, forming a part thereof.

The figure is a plan view of a piece of fabric showing my new design. The rectangle formed by the dot and dash lines defines the repeated pattern.

I claim:

The ornamental design for a textile fabric or similar article as shown and described.

JOHNNYE LEE VORHAUER.
